CARR D. CONDON, OF BOONE, IOWA.

MOVING-PICTURE APPARATUS.

1,123,689.

Specification of Letters Patent.

Patented Jan. 5, 1915.

Application filed January 16, 1914. Serial No. 812,415.

To all whom it may concern:-

Be it known that I, CARR D. CONDON, a citizen of the United States, and a resident of Boone, in the county of Boone and State 5 of Iowa, have made certain new and useful Improvements in Moving-Picture Apparatus, of which the following is a specification.

My present invention relates to improvements in moving picture apparatus, and 10 particularly to that class of moving picture apparatus in which the film is fed downwardly on to and partially around an upper continuously driven feed roller, and in which an idle presser roll is disposed adjacent to this feed roll for the purpose of putting the film thereon, it being well known that the film is provided with series of apertures along its opposite edges and the feed roll has circular series of spurs or projections 15 adjacent its opposite ends which cooperate with these film apertures, and it being further well known that the presser roll is mounted upon a bracket fulcrumed on the frame of the machine in such manner 20 as to permit of the movement of the presser roll away from the feed roll when it is desired to thread a film through the machine.

The above arrangement in practical use 25 has given rise to a serious and considerable disadvantage, namely in danger of adherence of a portion of the film to the feed roll and its passage almost completely around said roll, the usual loop formed between the upper continuously driven feed roll and the 30 lower intermittently driven roll enabling this action to take place, causing frequent breakage of the film and interruption in the projection of the picture series. In order to obviate this difficulty and disadvantage 35 it is the object of my present invention to supplement the parts mentioned with a "taking off" roll and to insure the desired release of the film from the feed roll and to thus act in a manner substantially 40 opposite to that of the presser roll which is in effect a "putting on" roll.

It is a further object of my invention to 45 mount the "taking off" roll upon a member which will form the fulcrum of the bracket upon which the presser roll or "putting on" roll is carried.

In the accompanying drawings which 50 illustrate my invention, Figure 1 is a perspective view illustrating certain parts of a moving picture apparatus in order that the 55 relative positions of the frame and the parts

immediately effected by my invention may be clearly seen, Fig. 2 is an end elevation of the upper feed roll and the "putting on" and "taking off" rolls with their supporting bracket, these latter rolls being partly broken away and in section, Fig. 3 is a vertical section taken through the parts shown in Fig. 2 substantially on line 3—3 of said figure, and, Fig. 4 is a detail perspective view 65 of the supporting bracket and "putting on" roll and illustrating the "taking off" roll and its parts in detached relation.

Referring now to these figures and particularly to Figs. 1 and 2, in the type of apparatus to which my invention is applied, the film strip indicated at A is fed downwardly around an idler a disposed forwardly on the upper continuously driven feed roll B and is extended rearwardly over 70 the upper portion of this feed roll and pressed into contact with the said feed roll in order to effectively engage the spurs b of the latter with the side apertures of the strip, by means of a presser roll C mounted 75 upon a bracket D, which bracket is acted upon by a spring E and is fulcrumed upon the frame of the machine so that it may be moved away from the feed roll and against the tension of spring E to the position 80 shown in dotted lines in Fig. 2 when it is desired to thread a film strip through the operating parts.

It will be seen that the presser roll C is 85 as usual provided with enlarged circumferentially grooved end portions c and that, by virtue of spring E, the presser roll is firmly though elastically held against the film strip and operates to put the said strip on the feed roll B. Due to this arrangement it 90 has been found that the film strip, which is intended to pass over only a small portion of the surface of the feed roll, will frequently adhere thereto and pass around therewith, as indicated in dotted lines in 95 Fig. 2, causing an acute angular bend in the film strip where it is intended that the same shall extend rearwardly and downwardly in a full loop, as shown in full lines in said figure. In order to defeat this I provide a 100 "taking off" roll F, the particular structure of this roll itself being identical with that of the roll C, and in order that such a roll may be conveniently associated with the bracket D now in use, I preferably mount 105 this roll F upon an arbor F' having an outer slotted head f and an inner threaded end f'

adapted to pass through a split spring bushing *d* disposed within the pivoted opening of the bracket, it being intended that this threaded inner end of the screw arbor shall 5 extend through the pivoted opening of the bracket and screw into a threaded opening in the frame of the machine for the reception of the same. By referring to Figs. 1 and 2 it will thus be seen that the "taking 10 off" roll F is in position to receive the film strip thereover, at a point immediately in the rear of the feed roll B and that this roll acts to effectively prevent the film from falling around the feed roll and the breaking of 15 the film strip when the next intermittent movement of the lower feed roll causes a jerk upon the strip.

I claim:

1. In moving picture apparatus, the combination of a feed roll partially around which the film strip is carried, a presser roll 20 engaging the film at a point adjacent to the feed roll for putting the said film on to the said roll, a bracket which carries the said 25 presser roll having an opening therethrough, a screw extending through the bracket opening for pivotally securing the bracket upon a portion of the frame of the apparatus, and having an elongated shank 30 and a head at its outer end, and a roll journaled upon the shank of said screw adja-

cent to the feed roll and engaging the film strip at a point beyond the presser roll to separate the film from the feed roll.

2. In moving picture apparatus, the combination of a feed roll partially around which the film strip is carried, a presser roll 35 engaging the film strip to put the same on the feed roll, a bracket which carries the said presser roll, a second roll engaging the film strip at a point beyond the presser roll 40 to separate the same from the feed roll, and a member upon which the said second roll is journaled, extending through the bracket and forming a fulcrum upon which the latter is movable to move the presser roll toward and away from the feed roll.

3. In moving picture apparatus, the combination of a feed roll partially around which the film strip is carried, a "putting on" 50 roll arranged to press the film strip against the feed roll, a "taking off" roll arranged to separate the film strip from the feed roll after its passage beyond the "putting on" roll, and a bracket fulcrumed at 55 a point adjacent to the feed roll and in connection with which the said "putting on" and "taking off" rolls are mounted.
